UNITED STATES PATENT OFFICE.

WILLIAM C. BENSON, OF OWENSVILLE, INDIANA.

RAILROAD-TIE WITH CUSHIONS.

1,093,308.

Specification of Letters Patent. Patented Apr. 14, 1914.

Application filed December 18, 1913. Serial No. 807,512.

To all whom it may concern:

Be it known that I, WILLIAM C. BENSON, a citizen of the United States, residing at Owensville, in the county of Gibson and State of Indiana, have invented a new and useful Railroad-Tie with Cushions, of which the following is a specification.

The present invention appertains generally to railroad ties, and aims to provide a novel and improved cushioned metallic tie.

The present invention aims to provide a railroad tie of unique construction, having novel rail engaging or holding means, and rail cushions.

15 A further object of the present invention is to provide a tie structure embodying a novel assemblage of parts whereby the rails may be conveniently secured to the tie, and whereby the tie may be effectively supported on the road bed.

It is also within the scope of the present invention to provide a tie structure which will be comparatively simple, durable and inexpensive in construction, as well as being 25 convenient, practical and efficient in use.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

40 Figure 1 is a plan view of the improved tie. Fig. 2 is a side elevation thereof, partly in section, the section being taken on the line 2—2 of Fig. 1. Fig. 3 is a fragmental plan view of one of the tie elements or sections, illustrating the manner of attaching the same to the rail.

In carrying out the present invention, the cross tie embodies a pair of juxtaposed parallel strips or bars 1, which are preferably 45 provided with the strengthening corrugations 2. Each of the strips 1 is provided at

one end with an angular plate or head 3, and at its other end, with an angular plate or head 4, the plates 3 and 4 being rectangular, and projecting in the same direction, or toward the same side of the strip 1. The plates 3 are provided with central countersunk openings 5, while the plates 4 are provided with central openings 6 adapted to align or register with the openings 5, as will 55 hereinafter appear. Each of the plates 3 is further provided with an upstanding hook 7 at its outer edge, and in alignment with the corresponding strip 1, and with a second or similar hook 8 at its inner edge and diagonally opposite the hook 7.

The plates 3 and 4 are approximately of the width of the base flanges of the rails R, while the hooks 7 and 8 of the plate 3 are spaced diagonally apart for a distance 60 slightly greater than the widths of the base flanges of the rails for the purposes which will hereinafter appear.

The present invention further includes a pair of sleepers or pillars 9 of concrete or 65 other suitable material, which are preferably of frusto-pyramidal formation, the bases of the pillars or blocks 9 being adapted to rest upon the road bed, or to be embedded or planted therein.

80 Suitable cushion blocks 10 are provided, which may be of wood, felt, or other suitable compressible material, the said blocks being of outlines similar to the plates 3 and 4. Locking pins or securing members 11 are 85 also employed for securing the tie sections or strips 1 together, with the cushions 10, and for attaching the said parts to the sleepers or pillars 9.

The two sections of the tie are duplicates 90 of one another, whereby they may be formed with like dies, or other tools, the tie sections being readily formed from sheet metal.

In assembling the several parts of the structure, it being understood that the sleepers or pillars 9 have been mounted upon or embedded within the road bed at the proper positions, the pins or bolts 11 are passed downwardly through the apertures or openings 5 of the plates 3, the heads of the bolts 95 or pins 11 being countersunk so as to fit or pins 11 being countersunk so as to fit flush with the faces or upper surfaces of the

- said plates. The plates 3 are then applied to the bottom of the rails at an angular position, as seen in Fig. 1, so that each strip or bar 1 stands at an acute angle with respect 5 to the rail, which will permit the base flange of the rail to drop between the hooks 7 and 8, and then by swinging the strip 1 at right angles to the rail, the hooks 7 and 8 will engage over the edges of the base flange, to 10 lock the rail upon the plate 3. After both of the tie sections have thus been engaged to the rail, the plates 4 are engaged to the lower ends of the pins or bolts 11, the pillow or cushion blocks 10 having first been inserted 15 between the plates 3 and 4. This will lock the tie sections together, and will also secure the pillow or cushion blocks between the plates 3 and 4 at the ends of the tie. The strips or bars 1 will be disposed side by side, and will be slightly and oppositely inclined, the plates 3 and 4 of the two strips 1 projecting in opposite directions and being spaced and superimposed with the cushion blocks 10 therebetween. The lower ends of 20 the locking pins or bolts 11 are then inserted into proper bores or sockets provided in the upper ends of the sleepers or pillars 9, whereby the tie will be secured to the sleepers or pillars, as will be apparent. 25
- 30 If desired, the sleepers or pillars 9 may have nuts or other similar members 12 embedded therein, for the threaded or other engagement of the pins 11, it being noted that the sleepers or pillars can be rotated to 35 thread the nuts 12 upon the pins 11.
- The present tie will thus carry out the objects aimed at in a desirable and efficacious manner, as will be apparent without further comment.
- 40 Having thus described the invention, what is claimed as new is;—
1. In a railroad tie, a pair of oppositely inclined cross strips having superimposed end plates, and cushions disposed between the said plates.
  2. In a railroad tie, a pair of oppositely inclined cross strips having superimposed end plates, cushions disposed between the said plates, the upper plates having rail holding means, and securing means engageable with the superimposed end plates and cushions of each set.
  3. A railroad tie structure embodying a pair of pillars, a pair of cross strips having superimposed end plates, the lower plates resting on the pillars, cushions disposed between the plates, and securing means engaging through the plates and cushions and taking into the pillars.
  4. A railroad tie structure embodying a pair of pillars, a pair of cross strips having superimposed end plates, the lower plates resting on the pillars, cushions disposed between the plates, and securing means engag-

ing through the plates and cushions and taking into the pillars, the upper plates having means engageable over the edges of the rail base flanges. 65

5. In a railroad tie, a pair of strips disposed side by side and having angular plates at their ends, the plates of the two strips projecting in opposite directions and being superimposed, and cushions disposed between said plates. 70

6. In a railroad tie, a pair of strips disposed side by side and having angular plates at their ends, the plates of the two strips projecting in opposite directions and being superimposed, and cushions disposed between the said plates, the upper plates having rail holding means. 75

7. In a railroad tie structure, a pair of pillars, a pair of cross strips disposed side by side and each having angular plates at its ends, the plates of the two strips projecting in opposite directions and being superimposed, the lower plates resting on the pillars, cushions disposed between the plates, and securing means engaged through the plates and cushions and taking into the pillars. 85

8. In a railroad tie structure, a pair of pillars, a pair of cross strips disposed side by side and each having angular plates at its ends, the plates of the two strips projecting in opposite directions and being superimposed, the lower plates resting on the pillars, cushions disposed between the plates, and securing means engaged through the upper plates and cushions and taking into the pillars, the plates having means at their edges for engaging over the base flanges of the rails. 95

9. In a railroad tie, a pair of cross members each having a plate at one end to receive a rail thereon, said plates each having a pair of diagonally disposed hooks at its edges, and the other ends of the cross members projecting below the said plates and securing means for connecting the plates and last mentioned ends of the said members. 105

10. In a railroad tie, a pair of oppositely inclined cross strips each having angular plates at its ends, the plates of the two strips projecting in opposite directions and being superimposed, each upper plate having a hook at its outer edge in alinement with the corresponding strip, and having a hook at its inner edge diagonally opposite the aforesaid hook, and securing members engageable through the superimposed plates. 115

11. In a railroad tie, a pair of cross strips each having angular plates at its ends, the plates of the two strips projecting in opposite directions and being superimposed, each upper plate having a hook at its outer edge in alinement with the corresponding strip, and having a hook at its inner edge diag- 125

nally opposite the aforesaid hook, pillars upon which the lowermost plates rest, cushions between the superimposed plates, and securing members engagin g through the 5 plates and cushions and taking into the pillars.

In testimony that I claim the foregoing

as my own, I have hereto affixed my signature in the presence of two witnesses.

WILLIAM C. BENSON.
